APPLYING REINFORCING STRIP TO SLIDE FASTENERS

Frank Campbell Rutherford, St. Catharines, Ontario, Canada, assignor to Lightning Fastener Company, Limited, St. Catharines, Ontario, Canada

Application March 22, 1939, Serial No. 263,571

5 Claims. (Cl. 154—1)

The invention relates to improvements in methods and means for applying reinforcing strips to slide fasteners. The fastener having the reinforcing strip with which the invention is concerned has been disclosed in United States Patent No. 1,964,485, to Seaver, issued June 26, 1934. That invention consists broadly of a fastener comprising a pair of flexible stringers provided with interlocking elements adapted to be interlocked by a slider engaging the elements and a piece of tape secured transversely across the stringer in the vicinity of the normally closed end which serves, when the fastener is sewn in a garment or the like, to relieve any strain on the closed end of the fastener, particularly when the fastener is opened.

It is an object of the present invention to devise a novel method of bonding the reinforcing strip to the stringers of such a fastener and to provide a machine whereby the method may be efficiently carried out.

It is also an object to devise such a method which may be applicable for the convenient and rapid bonding together of any two layers of fabric or the like.

With the above and other objects, which will hereinafter become apparent as the specification proceeds, in view the invention consists of the construction and arrangement all as hereinafter more particularly described and illustrated with reference to the accompanying drawings, in which:

Fig. 1 is a side elevational view of a machine for carrying out my method;

Fig. 2 is a front elevational view thereof;

Fig. 3 is a fragmentary view on an enlarged scale of a detail of the machine;

Fig. 4 is a transverse sectional view, taken along the line 4—4 of Fig. 1, of a solvent tank on the machine; and

Fig. 5 is a fragmentary view showing a pair of fasteners with the reinforcing tape secured thereto as produced by my machine.

Like characters of reference designate corresponding parts in the different views.

As shown in Fig. 5, the invention consists in bonding across the stringers 1, 1 of a slide fastener, which has the customary interlocking members 2 and may have a bottom stop member 3 for connecting the closed end of the fastener, a continuous length of reinforcing tape 4. The tape 4 is bonded to the stringer 1, 1 by laying one or more soluble filaments 5 between the tape and the fastener stringer, wetting the stringer or the tape in the vicinity of the filaments to

10 dissolve the filament material, pressing the tape firmly on the stringer to cause the dissolved filament material to penetrate the material of the tape and stringer and maintaining the relative positions of the parts while any excess solvent evaporates, to leave the parts firmly bonded together. I have found that a yarn composed of cellulose acetate makes a readily obtainable and effective soluble filament for this purpose as it may be readily dissolved in acetone, among other solvents.

15 A machine for carrying out these operations may consist, as shown in Figs. 1 to 4, of a frame 6 on which is journalled a drum 7 provided with grooves 8, each adapted to receive the elements 2 of one fastener. In each groove 8 is provided a stop pin 9 which serves to locate the fastener with the innermost elements 2, or bottom stop 3, as the case may be, all positioned thereagainst with the tape receiving areas of all the fasteners in a line around the periphery of the drum. A roller 10 journalled on the frame serves to guide a continuous length of tape 4 across the tape receiving portions of the fastener, when the drum is revolved as indicated by the arrow in Fig. 1, the spacing of the roller 10 from the drum 7 being such as to firmly press the tape against each fastener as the fastener passes under the roller. The yarn 5 may be led from a supply spool 11 through guides 12 over the tape on the roller 10 to lie between the tape and the fastener. Solvent may be supplied to the areas to be bonded by passing the tape 4 through a tank 13 containing a solvent, the level of which is maintained by an 20 orthodox constant level device which includes a reservoir 14 provided with a delivery tube 15 which terminates in the tank 13 at the desired level for the solvent. Rollers 16 and 17 journalled in the tank locate the tape 4 thereover, and by 25 means of a roller 18 carried in a bracket 19, which may be removably located in the tank by means of a pin 20 and a threaded projection 21 provided with a wing nut 22 received in a slot 23 in the tank, a loop of the tape may be held below the 30 surface of the solvent. The tape may be obtained from a reel 24 carried on the frame 6 and may be conveniently threaded under a roller 25 and through a guide 26 to the tank.

35 After the tape has been pressed against the fastener by passing under the roller 18, the tape and fastener may be maintained in the same relative positions until any excess solvent has evaporated by means of a flexible band 27, preferably made of spring steel, secured at one extremity to a post 28 in the frame and passing around the

drum periphery and over a second post 29, being held resiliently against the drum periphery by means such as a coil spring 30 tensioned between the end of the band and the frame. Such band is positioned to overlie the length of tape connecting the fasteners and, if desired, a second similar band 31 may be provided in spaced relation thereto on the drum periphery to prevent the free ends of the fastener from fouling the working parts of the machine. If desired, the portion of the drum periphery in which the bonded fasteners are carried may be surrounded by a hood 32 within which is disposed a heater element 33 to accelerate evaporation of the solvent.

As shown best in Fig. 3, a slot 34 may be provided in one end of the drum to facilitate starting of a length of tape through the machine. A knot 35 may be tied in the free end of the tape to be threaded and by inserting the end of the tape laterally into the slot and tensioning the tape until the knot engages the inside of the drum, when the drum is rotated the tape will be fed under the roller 10 and the band 27 in the proper alignment.

To operate the machine, the reinforcing tape 4 is pulled from the reel, passed under the roller 25, through the guide 26, over the rollers 16 and 17, the end is caught in the slot 34, as above described, and by rotating the drum 7 in the direction of the arrow in Fig. 1, the tape is started into the machine. The yarn is then threaded through the guides 12 and started underneath the tape on the roller 10. Then on forcing a loop of the tape 4 down into the tank 13 against the roller 18 by clamping the bracket 19 in position in the tank, the machine is ready for operation. After turning the drum until the moistened portion of the tape reaches the roller 10, fasteners are laid in each groove 8 in succession before each slot passes under the roller 10, each fastener being properly located with respect to the roller 10 by abutting the bottom stop or the end elements 2 thereof against a pin 9. As each fastener passes under the roller 10 the yarn 5 partially dissolves in the solvent carried by the tape 4, and as the roller 10 presses the tape against the fastener the yarn material is forced into the pores of the tape and the fastener. As the fastener and tape leave the roller 10 the band 27 maintains the pressure until, by the time the fasteners have reached the point on the periphery of the drum at which they are released by the band, the excess solvent has evaporated to leave the tape firmly bonded to the fasteners. To complete the tape attachment, it is only necessary to sever the continuous tape between each pair of adjacent fasteners.

According to my improved method of bonding fabric material together, a bond may be produced very rapidly and efficiently and without any possibility of smearing the bonding material on parts of the bonded articles on which it is not desired. For applying reinforcing tapes to fasteners, in particular, the method, using the machine disclosed therefor, is very simple and capable of being performed repeatedly and very rapidly so that a high output of finished articles may be obtained from one machine.

While I have shown and described one em- 70

bodiment which my invention may assume in practice, it will be understood that such embodiment is merely for purposes of illustration and description and that various other forms may be devised within the scope of my invention as defined in the appended claims.

What I claim as my invention is:

1. A machine for applying to slide fasteners, which include a pair of flexible stringers each provided with a series of interlocking elements disposed in interlocking relation, a transverse reinforcing tape, comprising fastener supporting means, means for supporting a length of tape transversely of the fastener, means on the fastener supporting means for locating the tape receiving area of the fastener in register with the tape supporting means, means for guiding a soluble filament between the length of tape carried by the tape supporting means and the fastener carried by the fastener supporting means, means for supplying a solvent for the filament thereto and means for relatively moving the fastener supporting means and the tape supporting means for simultaneously feeding the filament and pressing the tape against the fastener with the filament therebetween.
2. A machine as claimed in claim 1 wherein the solvent applying means comprises a solvent tank, and means for guiding the tape therethrough prior to its application to the fasteners.
3. A machine for applying to slide fasteners, which include a pair of flexible stringers each provided with a series of interlocking elements disposed in interlocking relation, a transverse reinforcing tape, comprising a supporting frame, a drum rotatable thereon and having a plurality of spaced apart peripheral grooves parallel to the drum axis each adapted to receive the interlocked elements of a fastener, a stop member in each groove for locating the fasteners with their tape receiving areas uniformly spaced from one end of the drum, a roller journaled on the frame with its axis parallel to the drum axis, means for guiding a continuous length of reinforcing tape over the roller, the spacing of the roller from the drum being such that rotation of the drum when loaded with fasteners feeds the tape across the tape receiving areas of the fasteners and presses the tape firmly thereagainst as each fastener passes the roller, means for guiding a soluble filament between the tape and the fasteners as the drum is rotated, means positioned in advance of the roller for supplying a solvent for the filament thereto and means for maintaining the relative positions of the fasteners and tape after the fasteners pass the roller until any excess solvent has evaporated.

4. A machine as claimed in claim 3 wherein the solvent supplying means comprises a solvent tank and means for guiding the continuous length of reinforcing tape therethrough before the tape reaches the roller.

5. A machine as claimed in claim 3 wherein the means for maintaining the relative positions of the fasteners and tape comprises a flexible band disposed around the drum periphery and overlying the continuous tape, and means for yieldably holding the band in contact therewith.

FRANK CAMPBELL RUTHERFORD.
